UNITED STATES PATENT OFFICE.

WESTERN UNDERWOOD, OF LOS ANGELES, CALIFORNIA.

DESIGN FOR A LIGHTING POST.

Application filed September 18, 1926. Serial No. 19,046. Term of patent 14 years.

To all whom it may concern:

Be it known that I, WESTERN UNDERWOOD, a citizen of the United States, residing at Los Angeles, in the county of Los Angeles and State of California, have invented a new, and original, and ornamental Design for a Lighting Post, of which the following is a specification, reference being had to the accompanying drawing, forming part thereof.

I claim:

The ornamental design for a lighting post, as shown.

WESTERN UNDERWOOD.
